UNITED STATES PATENT OFFICE.

OSCAR EMIL LINDROTH, OF LOS ANGELES, CALIFORNIA.

BROILER.

1,263,381.

Specification of Letters Patent. Patented Apr. 16, 1918.

Application filed June 12, 1917. Serial No. 174,220.

To all whom it may concern:

Be it known that I, OSCAR EMIL LINDROTH, a subject of the King of Sweden, residing at Los Angeles, in the county of Los Angeles and State of California, have invented new and useful Improvements in Broilers, of which the following is a specification.

This invention relates to a broiler adapted for use with gaseous fuel, and arranged for broiling from below.

Broilers using gaseous fuel have not heretofore been successfully used to broil from below. The reason for the failure to successfully use a broiler of this type has been as follows:—

The grease and juices dripping from the article being broiled fall upon the orifices or openings in the burners clogging them. If the burner orifices are protected by a shield, the juices drip upon the hot parts of the burner and are consumed, causing the article being broiled to become smoked and giving to it a burnt flavor.

It is an object of my invention to provide a broiler which will use gaseous fuel and broil from below without the disadvantages enumerated above.

A further object of my invention is to provide details of structure, whereby a compact, simple and durable broiler is obtained.

I accomplish these objects by means of the embodiment of my invention illustrated in the accompanying drawing, in which:—

Figure 1 is a plan view of the broiler with some of the broiler bars broken away to clearly show the position of the burner orifices. Fig. 2 is a section as seen on the line 2—2 of Fig. 1. Fig. 3 is a section as seen on the line 3—3 of Fig. 1. Fig. 4 is an isometric view of a cap which may be used with the bars.

Referring more particularly to the drawing, the broiler consists of a base indicated by A and a broiler grate indicated by B. The features of my invention reside more particularly in the base A, which carries the burner elements.

Referring particularly to the base A, it is preferably a cast metal structure and is shown of box shape and formed with a compartment 5. The compartment 5 serves as a cooling chamber through which cold water circulates. A pipe 6 enters the compartment 5 at one side and extends to a point close to the opposite side of the compartment.

ment. A nipple 7 for connection to a source of cold water supply is provided on the outer end of pipe 6. The water issues from an opening 8 which is provided with a nipple for connection with drain pipes.

The upper surface of the base A is provided with a series of longitudinally extending ribs 9 which have bores extending the length thereof. The ends of the bores are closed with plugs 10, this permitting cleaning of the bores. The other ends of the bores are connected to fittings which include air mixing devices, gas valves and a manifold. The fittings just described are of the usual type, well known in the art, and for that reason will not be further described. They are indicated generally by reference numeral 11. Extending along the length of the ribs 9 are apertures 12 connecting with the bores. The apertures 12 may be replaced by slots extending the length of the bores. It is merely essential that there be openings through which the fuel may issue. A trough 14 is formed on the base and is provided for the purpose of catching the juices which drain from the top of the base.

Placed above the base A is the broiler grate B. Grate B is comprised of cross bars 15 and 16, upon which are disposed the broiler bars 17 for supporting the article to be broiled. Grate bars 17 are triangular in section, and are hollowed out on the lower face as indicated by 18 in Figs. 2 and 3. The grate bars are formed with lugs 19 and 20 at the ends which are bored to receive bolts, so that the bars may be bolted to the cross bars 15 and 16. Corner posts 21 support the grate above the base. These posts are threaded and are engaged with threaded apertures which are formed in the ends of cross bars 15 and 16. Kerfs are formed in the heads of the posts, so that by rotating the posts, the distance of the grate above the base may be adjusted.

I have also provided caps, one of which is shown particularly in Fig. 4 and indicated by 22. A cap may be placed over a grate bar and thereby add to its thickness also its heat conductivity, so that articles such as oysters, which do not require as intense heat as other articles may be broiled. A cap is provided for each bar.

It is evident that when the article to be broiled is placed upon the grate bars 17, the juices which drip therefrom during the

broiling process will be deflected from the orifices in the burner and will drop upon the spaces between the ribs 9. In this location the juices would burn, if it were not 5 for the cooling produced by the water circulating in the base. The juices will drain from the top of the base into trough 14 and will be conducted away.

It is obvious that I have provided a 10 broiler which is simple in structure and therefore cheap to manufacture. There is no plate interposed between the article to be broiled and the flame. The specific form of broiler that I have shown in the drawing is 15 merely for the purpose of illustration. Various changes may be made in the mechanical structure to accommodate the broiler to articles of various sizes and fuels of various character.

20 What I claim is:—

1. A broiler comprising a base having a burner formed thereon and cooling means for said base, said burners having jet orifices for directing the flames upwardly, and 25 a grate for articles to be broiled, said grate spaced above said base and including bars disposed above the orifices in said burner to shield the same from drippings, said base arranged to catch the drippings on its 30 cooled portion.

2. A broiler comprising a base having a burner formed thereon and a water jacket for cooling said burner, said burners having jet orifices for directing the flames upwardly, and a grate for articles to be 35 broiled, said grate being spaced above said base and including bars disposed over the orifices in said burner to shield the same

from drippings, said base arranged to catch the drippings on its cooled portion. 40

3. A broiler comprising a base having a burner formed thereon and cooling means for said base, said burners having jet orifices for directing the flames upwardly, a 45 grate for articles to be broiled, said grate being spaced above said base and including bars disposed above the orifices in said burner to shield the same from drippings, and cap for said bars, said base arranged to catch the drippings on its cooled portion. 50

4. A broiler comprising a base having a burner formed thereon and a water jacket for cooling said burner, said burners having jet orifices for directing the flames upwardly, a 55 grate for articles to be broiled, said grate being spaced above said base and including bars disposed over the orifices in said burner to shield the same from drippings, and caps for said bars, said base arranged to catch the drippings on its cooled 60 portion.

5. A broiler comprising a hollow base provided with means for circulating water therethrough to cool the same, burners formed on the upper wall of said base, said 65 burners having jet orifices for directing the flames upwardly, and a grate for articles to be broiled, said grate spaced above said base and including bars disposed above the orifices in said burners to shield the same from 70 drippings, said base arranged to catch the drippings on its cooled portion.

In witness that I claim the foregoing, I have hereunto subscribed my name, this 31st day of May, 1917.

OSCAR EMIL LINDROTH.
